UNITED STATES PATENT OFFICE.

HARRY R. HOLDEMAN, OF LOS ANGELES, CALIFORNIA. ASSIGNOR TO THE J. M. FELDMAN CO. INC., OF LOS ANGELES, CALIFORNIA.

DESIGN FOR AN ITALIAN EFFECT LIGHTING-FIXTURE PLATE.

Application filed April 18, 1927. Serial No. 21,633. Term of patent 3½ years.

To all whom it may concern:

Be it known that I, HARRY R. HOLDEMAN, a citizen of the United States, residing at Los Angeles, in the county of Los Angeles and State of California, have invented a new, original, and ornamental Design for Italian Effect Lighting-Fixture Plates, of which the following is a specification, reference being had to the accompanying drawing, forming part thereof.

The figure is a plan view of an Italian effect lighting fixture plate showing my new design.

I claim:

The ornamental design for an Italian effect lighting fixture plate as shown.

HARRY R. HOLDEMAN.
